SLIDE FASTENER MACHINES

Alexander M. Brown, New Britain, Conn.

Application February 5, 1947, Serial No. 726,624

44 Claims. (Cl. 29—34)

The invention relates to the manufacture of slide fastener parts, and more particularly to a machine for forming and shaping slide fastener elements and attaching them on a tape. The invention more specifically contemplates an arrangement which cuts from a suitably shaped strip of wire an element blank having a head and diverging legs, forms a recess and a projection on the head for interlocking with similar parts on another fastener element, and clamps the legs on a tape to form the finished fastener part.

I am aware that various types of machines for carrying out these steps have been devised. All such machines however, have intermittently moving reciprocating or oscillating parts, and their operation requires substantial force in overcoming the inertia of the parts at the beginning and end of each movement. This limits the speed of such machines and causes rapid wear on the parts.

A primary object of the present invention is to provide a machine for making slide fastener parts in which each part of the machine moves continuously in the same direction and at constant speed. More specifically, the invention contemplates a mechanism formed of a series of rotating members which cut a blank from a fastener wire, form it and set it on a tape, while carrying the blank along from each operation to the next. Such an arrangement can operate at high speed without excess wear on the machine parts and without substantial vibration. Furthermore, the power required to operate the machine is comparatively small, and the machine can be started easily after any stoppage.

Another object of the invention is to provide, in a machine for setting fastener elements on a tape, a simple and accurate mechanism for producing gap-spacing between series of adjacent elements on the tape. This part of the device is arranged to assure gaps of the proper length at any speed of the machine, and to allow easy interchangeability of parts for varying the length of the gap.

The machine is preferably devised so that each rotating part is acting on or carrying a plurality of fastener elements at once, thus increasing the output of the machine for a given speed of the rotating parts.

Still another object of the invention is to provide a novel and effective arrangement for setting fastener elements on a tape, this including a device for carrying the element in a circle on a continuously moving rotating member, feeding the tape across the circle of rotation of such member and substantially radially of such circle, and applying the element to and clamping it on the tape while the carrying member continues to rotate.

A further object of the invention is to provide a mechanism for forming a slide fastener element blank in which the forming device also acts at least in part as a carrier for the element.

Other objects and advantages of the invention will appear more fully from the following description, especially when taken in conjunction with the accompanying drawings which form a part thereof.

2

In the drawings:

Figure 1 is a top plan view of a machine embodying my invention;

Figure 2 is a side elevation, from the top of Figure 1;

Figure 3 is a perspective view of a part of the cutting roll;

Figure 4 is a similar view of the gap spacing mechanism;

Figure 5 is a fragmentary perspective view of the die cutter and die;

Figure 6 is a similar view of the meeting point of the die cutter roll with the carrier roll;

Figure 7 is a similar view of the meeting point of the carrier roll with the forming roll;

Figure 8 is a detail of the holding mechanism for the forming roll;

Figure 9 is a perspective view of the meeting point of the forming roll with the setting roll;

Figures 10 and 11 show in side elevation the setting mechanism in two stages of its operation;

Figure 12 shows in top plan view a modified form of setting roll, and

Figures 13 and 14 show in side elevation the setting mechanism of this modification in two stages of its operation.

The device in general consists of a series of rotating members or drums including a cutting drum 2, a carrier drum 4, a forming drum 6, and a setting drum 8. These drums are mounted respectively on shafts 10, 12, 14, and 16. Shaft 10 is driven by a pulley 18 and drives through gears 20, 24, 26, and 28 respectively shafts 12, 14, and 16, at the same speed of rotation as shaft 10, shafts 10 and 14 turning in one direction and shafts 12, 16 in the opposite direction. Shaft 14 through gearing 23 drives countershaft 22.

Drum 2 has on its peripheral surface four cutting dies 30 of a shape to receive the end of the preformed wire 32 (see Figure 5) having a head portion and diverging leg portions. This wire is fed past a stationary supporting knife 34, past which members 30 move upon the rotation of drum 2. The depth to which the wire can enter into die member 30 is controlled by a plate 36 arranged in a slot in drum 2 and pivoted at 38, the inner or rear edge of this plate 36 resting against the body of the drum. The wire is allowed to enter the space in the die member by an amount equal to the thickness of the desired fastener element 40 (see Figure 5).

The wire 32 is fed radially to drum 2 by the feeding mechanism shown in Figure 1. This includes a wheel 42 mounted on a shaft 44 and having a generally U-shaped groove in its peripheral surface adapted to engage the head side (left-hand side of Figure 5) of wire 32. Opposite this wheel is a second wheel 46 mounted on shaft 50, in arms 52 pivoted at 54 on the frame of the machine.

Wheel 46 has an edge fitting within the groove between the leg portions of the wire. It is normally urged against the wire by an adjustable coil spring 56 so that the wire is frictionally held between the two wheels. Shaft 44 is driven through gearing 55 from the shaft 22.

Supported above the main frame of the machine by pins 60 are plates 62 which overlie the center of the periphery of drum 2. These plates fit closely to the outer surface of die member 30, and prevent the element cut off by the die member from being thrown off by centrifugal force. Pins 64 extend up vertically from slightly larger holes 66 in members 36 and through considerably larger holes 68 in the body of drum 2 to a point considerably above the upper surface of the drum. These pins are so arranged that when their top ends are pushed inwardly towards the center of the drum they will fulcrum on the upper edges of holes 68 to cause the free ends of members 36 to swing outwardly.

70

After a rotation of 270° from the cutting-off point opposite the die cutting knife 34, in the direction of the arrow of Figure 1, the die member 30 comes adjacent the drum 4 (see Figure 6). At this point one of the holders 70 mounted on the periphery of the carrier drum 4 comes opposite the die member 30. At this point plate 62 terminates so that the element 40 is no longer held against discharge from the die member 30 by the action of centrifugal force and can be thrown off into the holder 70. To assure the transfer of the element to the holder 70, however, there is provided a plate member 72 extending over the surface of the drum and having an inclined surface 74 which engages the upper end of pin 64 of the plate 36 which is closest to the carrier drum 4. This engagement tilts the top of the pin 64 inwardly around the upper edge of hole 68 as a fulcrum and rocks the plate 36 outwardly so as to push element 40 positively out of the die member 30 and into the holder 70.

As soon as pin 64 passes surface 74, the pressure of wire 32 against the forward end of plate 36 pushes the plate back to its withdrawn position, in which the member 30 can again engage the end of the wire to cut off another blank element.

Carrier drum 4 then carries the element around in the direction of the arrow of Figure 1. The escape of the element from the holder 70 is prevented by a plate 76 which lies opposite the center of the periphery of drum 4 and is supported above the frame of the machine by suitable bolts 78. This plate extends half-way around the periphery of the carrier.

After a travel of 180° , the carrier 70 comes to a point adjacent the forming drum 6 (see Figure 7). The forming drum has extending from its periphery a crotch engaging member 80 capable of fitting between the legs of element 40 and closely adjacent to it a punch member 82 tapering to a point having the desired shape of the recess to be formed in the fastener element. These two members meet the carrier 70, the crotch engaging member 80 first entering between the legs of the element to hold it in the carrier 70 and the punch 82 then engaging the head of the element to form the recess and projection in the head of the element. This action is in itself normally sufficient to transfer the formed element to the forming drum 6 where it would be held by members 80 and 82. However, to insure this transfer, there are provided rails or holders 84, 86 having a slot 88 between them into which the projection formed on the fastener element can fit. At the ends, slot 88 is widened sufficiently to permit the passage of the carrier 70 between the ends of rails 84, 86. As shown in Figure 7, however, the legs of the fastener element will engage the inner faces of these rails. Thus as the parts continue to turn the fastener element will be positively removed from the holder 70 (which has a recess 71 so as to act as a die for the die punch 82) and transferred to the forming drum 6.

Rail 84 is upstanding from the edge of a plate 90 supported on the frame of the machine by bolts 92. Rail 86 is supported above rail 84 by U-shaped members 94 (see Figure 8). These rails serve to hold the element on the forming drum during its passage of 180° to a point adjacent the setting drum 8.

Setting drum 8 has on its periphery four flat areas 96 (see Figure 9). The drum is formed of two parts carried by shaft 16 and separated by a slot 98. Pivoted on pins 100 on each of the flat surfaces 96 are clamping members 102 having converging opposed surfaces 104. Flat springs 106 arranged on the top and bottom faces of the drum rest on clamping members 102 and automatically hold them in the position shown in Figure 9. Pins 108 project outwardly from the members 102 on the side of pivot 100 opposite the clamping surfaces 104.

Spaced rails 110 run around the periphery of the drum 8 from the point adjacent drum 6 for 90° to the setting point. The space between these rails is sufficient to permit the passage of crotch engaging member 80 and form-

ing member 82, but not to allow the passage of the legs of the fastener element 40. When the fastener element comes opposite drum 8, it is engaged between the inclined surfaces 104 and its legs come against the inner faces of rails 110. It will thus be removed from elements 80 and 82 and transferred to the setting drum 8.

After a travel of 90° in the direction of the arrow of Figure 1, the element carried by the setting drum 8 reaches the setting point where it is to be applied to the tape (see Figures 10 and 11). The tape 111 is fed under a guide roller 112 through the slot 98 and past the plates 114 whose forward edges lie close to the periphery of drum 8 at the setting point. The bead 116 on the edge of the tape rests against the edges of plates 114 and the tape is thus guided past the setting point in a direction substantially radial to the axis of drum 8. From this point the tape passes on between a feed roller 118 mounted on shaft 120 and driven by gearing 122 from shaft 22 and a suitable counter roller 124 which holds the tape against the feed roller.

Also adjacent the setting point are two rails 126 having at their forward ends sloping surfaces 128 in the paths of pins 108. As the element 40 held by the surface 104 reaches the setting point, its legs straddle the bead of the tape as shown in Figure 10. The tape will then stop the movement of the element 40, while drum 8 continues to rotate. At the same time, pins 108 engage surfaces 128 of rails 126. Further movement of the drum 8 causes the clamping members 102 to pivot as shown in Figure 11 against the action of springs 106, and the sloping surfaces 104 move downwardly into parallel relationship, thus clamping the legs of the fastener element between them against the tape bead. As the drum is moving forward while the surfaces 104 are in effect moving backward on the drum during such swinging, the result is that the fastener is held stationary during this setting operation. When the setting is over, the members 102 will clear the fastener as shown in Figure 11, and will move around with the drum until pins 108 escape from rails 126 and springs 106 return clamping members 102 to their normal position.

Of course members 102 must pass the tape and the bead 116 at approximately 150° beyond the setting point (see upper right-hand corner of Figure 1). However, the space between surfaces 104 is almost sufficient for this purpose, and in addition members 102 can rock against the action of springs 106 to allow the passage of the bead between the two clamping members.

The mechanism as hereinbefore described is adequate for the purpose of setting fastener elements continuously on a tape. It is believed that its operation in general will be clear from the foregoing, but nevertheless a summary will be given here.

As the machine is driven, wire 32 is fed forward past die knife 34 and into the die member 30 (see Figure 5). As drum 2 revolves, it cuts off an element from the end of the wire and carries this element in die member 30 270° to a point adjacent carrier drum 4. At this point, pin 64 engages surface 74 and rocks member 36 to push the element out of the die member 30 and into the holder 70 on the carrier drum 4. The carrier drum rotating carries the element 40 180° to a point adjacent forming drum 6. As the crotch engaging member 80 and punch 82 meet the element held in member 70, they hold and form the element and at the same time pick it off the drum 4 to drum 6. This action is facilitated by rails 84 and 86 as shown in Figure 7. The formed element is carried by drum 6 through 180° to a point adjacent the setting drum 8 (see Figure 9). At this point the element is engaged between the surfaces 104 of setting and clamping members 102, and is removed from members 80, 82 by rails 110. Drum 8 carries the formed element 90° to the setting point where it comes astride of the bead 116 of the tape (see Figure 10). Meanwhile the tape has been fed through the proper amount by drum 118. As drum 8

continues to rotate, the setting elements are tilted as shown in Figure 11 to clamp the legs of the element on tape 111.

Obviously such an arrangement will continue to set the fastener elements one by one on the tape, this being accomplished in the machine shown herein four times at each revolution of the drums.

In the production of slide fastener tapes, it is usually necessary to form gaps in the spacing of the elements on the tape, so that the finished tape may be cut into sections and assembled into slide fasteners. This is accomplished by the gap spacing mechanism shown in Figures 1 and 4. It will be remembered that element 36 can be swung out to the outer edge of die member 30 by tilting pins 64. The spacing is accomplished by swinging out this member 36 at the point where wire 32 is fed to drum 2 so as to prevent the wire from entering the die member and thus to prevent the formation of the fastener element.

This is accomplished by a block 130 mounted on a shaft 132 supported in a member 134 above the frame of the machine. Block 130 has at its upper edge a curved surface 136 which, when the block is swung downwardly to the position shown in Figure 4, forms a continuation of curved surface 74. Normally however this free edge lies above the top of pins 64, being held in this raised position by a spring 138 engaging the end of lever 140 secured to shaft 132.

In order to rock the block 130 downwardly to interrupt the feed of the wire to the cutting drum 2, I provide an internally toothed ring gear 142 engaging a smaller gear 144 mounted on the end of shaft 22. Ring gear 142 has on its outer face one or more raised cam sections 146.

When the machine is in operation, ring gear 142 is turned by gear 144. Whenever one of cam sections 146 comes underneath lever 140, it raises this lever against the action of spring 138 as shown in Figure 4 and rocks block 130 downwardly to tilt pin 168 and prevent the feed of wire to the drum 2. Obviously the cam sections 146 may be as long or as short as desired, and thus can determine the spacing between groups of fastener elements on the tape and the number of elements in each such group. The arrangement shown in Figure 4 permits an easy change in this spacing by the removal of one ring gear from gear 144 and a substitution therefor of a gear having a different number of teeth or different spacing or length of the cam surfaces or both.

Figures 12 to 14 show a modified form of setting mechanism. In this arrangement, the setting drum 8' is again formed of two parts having a slot through them through which tape 111 is fed, and the tape is guided by plates 114. Drum 8' carries on its flat surface two rollers 150 mounted on pins 152, the space between these rollers being substantially equal to the width of the head of the fastener element but less than that of the extended legs. Pivoted at 154 are bent levers 156 the ends of which remote from the drum 8' are connected by coil spring 158. These levers are normally held outwardly with their ends adjacent drums 8' separated from each other by a distance equal to the distance between the extended legs of the fastener element 40. As drum 8' rotates, the legs of the fastener elements come up against the ends of levers 156 and at the same time straddle the bead 116 of the tape 111. The levers then block further movement of the element, while drum 8' continues to rotate. This continued rotation of the drum forces rollers 150 forward and squeezes the legs of the fastener between the two rollers and down on the tape bead (see Figure 14). The rollers also squeeze together the front ends of levers 156, so as to be able to pass these levers in the continued rotation of the drum. The element is thus set on the tape without stopping the rotation of the drum. As soon as the rollers have cleared the levers 156, spring 158 pulls these levers back to the position shown in Figure

13 where they will engage and stop the next element brought around to them by drum 8'.

The rest of the mechanism may operate in the same manner as that of Figure 1, the device of Figures 12 to 14 being an alternative of that shown in Figures 9 to 11.

While I have described herein some embodiments of my invention, I wish to be understood that I do not intend to limit myself thereby except within the scope of the claims hereto or hereafter appended.

I claim:

1. A machine for making slide fastener parts, comprising rotary mechanism for cutting off a blank having legs and a head portion from a generally V-shaped wire strip, rotary mechanism tangent to said cutting off mechanism for receiving a blank therefrom and for forming the head portion of said element, rotary mechanism tangent to said forming mechanism for receiving a formed blank therefrom and for clamping the legs of said element on a tape, and means to drive said mechanisms in synchronism with each other.

2. A machine for making slide fastener parts, comprising rotary mechanism for cutting off a blank having legs and a head portion from a generally V-shaped wire strip, rotary mechanism for feeding such wire strip to the first mechanism, rotary mechanism tangent to said cutting off mechanism for receiving a blank therefrom and for forming the head portion of said element, rotary mechanism tangent to said forming mechanism for receiving a formed blank therefrom and for clamping the legs of said element on a tape, mechanism for feeding a tape through said fourth mechanism, and means to drive said mechanism in synchronism with each other.

3. A machine for making slide fastener parts from a preformed wire strip, comprising rotary mechanism for cutting off a blank having legs and a head portion from a generally V-shaped wire strip, rotary mechanism tangent to said cutting off mechanism for receiving a blank therefrom and for forming the head portion of said element, rotary mechanism tangent to said forming mechanism for receiving a formed blank therefrom and for clamping the legs of said element on a tape, and means to drive said mechanisms in synchronism with each other; said first mechanism comprising a rotating member having a recess in its periphery of the shape of the cross-section of such wire strip, a stationary die knife adjacent the periphery of the radius of rotation of said die member, means to feed a preformed wire strip past said die knife to said die member radially thereof, and means to prevent escape of a blank from such recess between the cutting point and the point of tangency of said head forming mechanisms.

4. A machine for making slide fastener parts from a preformed wire strip, comprising rotary mechanism for cutting off a blank having legs and a head portion from a generally V-shaped wire strip, rotary mechanism tangent to said cutting off mechanism for receiving a blank therefrom and for forming the head portion of said element, rotary mechanism tangent to said forming mechanism for receiving a formed blank therefrom and for clamping the legs of said element on a tape, and means to drive said mechanisms in synchronism with each other; said first mechanism including a rotating member having means thereon to hold a slide fastener element in a position substantially tangent to the circle of rotation of said member with its legs pointing in the direction of rotation, means on the outside of at least a part of the periphery of said member to prevent said element from sliding therefrom under the action of centrifugal force, said second mechanism including a part adapted to receive said fastener element, said last means terminating short of the adjacent position of said member and part so that said fastener element may escape from said member to said part under the action of centrifugal force, a lever pivoted in said member and having a

portion located behind said element holding means, and means operable upon said lever after it has passed the end of said last means to swing said lever to ensure ejection of the fastener element from said holding means.

5. In a machine as claimed in claim 1, means to interrupt the feed of fastener elements to said first mechanism, operating means for said interrupting means, said operating means including a movable member, a gear, an inwardly toothed ring engaged upon said gear, said movable member engaging said ring, said ring having portions of different thickness to cause movement of said movable member so as to permit or prevent the feed of fastener elements.

6. A machine for making slide fastener parts from a preformed wire strip, comprising rotary mechanism for cutting off a blank having legs and a head portion from a generally V-shaped wire strip, rotary mechanism tangent to said cutting off mechanism for receiving a blank therefrom and for forming the head portion of said element, rotary mechanism tangent to said forming mechanism for receiving a formed blank therefrom and for clamping the legs of said element on a tape, and means to drive said mechanisms in synchronism with each other; said first mechanism comprising a rotating die member having a recess therein, a stationary die knife adjacent the periphery of the radius of rotation of said stationary die member, means to feed a preformed wire strip past said die knife to said die member, and means to interrupt the feed of wire strip to said die member, said means including a part movable into the recess of said die member, a movable member operatively connected to said part, a gear, an inwardly toothed ring engaged upon said gear, said movable member engaging said ring, said ring having portions of different thickness to cause movement of said movable member so as to permit or prevent the feed of wire strip.

7. In a machine for making slide fastener elements, a rotating member, a die member carried by said rotating member, means to rotate said rotating member, a die knife adjacent the periphery of the radius of rotation of said die member, said die member having an opening therein to receive the end of a preformed wire strip, means to feed a preformed wire strip past said die knife to said opening, a member movably mounted in said rotatable member and having a part located behind at least a part of said opening, means on the outside of a part of the periphery of said die member to prevent an element from sliding therefrom under the action of centrifugal force, a part adapted to receive said fastener element, said last means terminating short of the adjacent position of said die member and part so that said fastener member may escape from said die member to said part by the action of centrifugal force, and means operable upon said movable member after it has passed the end of said last means to move said member to ensure ejection of said fastener element from said die member.

8. In a machine for making slide fastener elements, a rotating member, a die member carried by said rotating member, means to rotate said rotating member, a stationary die knife adjacent the periphery of the radius of rotation of said die member, said die member having an opening therein to receive the end of a preformed wire strip, means to feed a preformed wire strip past said die knife to said opening, a member movably mounted in said rotatable member and having a part located behind at least a part of said opening, means selectively operable upon said movable member when said die member is opposite said die knife to move said movable member into said opening to prevent the feed of wire strip to said die member.

9. In a machine as claimed in claim 8, said last means including a movable part, a gear, an inwardly toothed ring engaged upon said gear, said movable part engaging said ring, said ring having portions of different thickness

to cause movement of said movable part so as to permit or prevent the feed of wire strip to said opening.

10. In a machine for making slide fastener elements, a rotating member, a die member carried by said rotating member, a stationary die knife adjacent the periphery of the radius of rotation of said die member, said die member having an opening therein to receive the end of a preformed wire strip past said die knife to said opening, a lever pivoted in said rotatable member and having a part located behind at least a part of said opening, and means operable upon said lever when said die member is opposite said die knife to swing the end of said lever into said opening to prevent the feed of said wire strip to said die member.

11. In a machine for making slide fastener elements, a rotating member, a die member carried by said rotating member, means to rotate said rotating member, a stationary die knife adjacent the periphery of the radius of rotation of said die member, said die member having an opening therein to receive the end of a preformed wire strip, means to feed a preformed wire strip past said die knife to said opening, a lever pivoted in said rotatable member and having a part located behind at least a part of said opening, means on the outside of a part of the periphery of said die member to prevent an element from sliding therefrom under the action of centrifugal force, a part adapted to receive said fastener element, said last means terminating short of the adjacent position of said die member and part so that said fastener member may escape from said die member to said part by the action of centrifugal force, means operable upon said lever after it has passed the end of said last means to swing said lever to ensure ejection of said fastener element from said die member, and means operable upon said lever when said die member is opposite said die knife to swing the end of said lever into said opening to prevent the feed of wire strip to said die member.

12. In a machine as claimed in claim 11, said last means including a movable part, a gear, an inwardly toothed ring engaged upon said gear, said movable part engaging said ring, said ring having portions of different thickness to cause movement of said movable part so as to permit or prevent the feed of wire strip to said opening.

13. A machine for making slide fastener parts comprising a rotating cutter part, a rotating forming part tangential to the cutter part, and a rotating setting part tangential to the forming part, means to drive said parts in synchronism with each other, said cutting part having a die member on its periphery, a stationary knife member adjacent the periphery of the cutting part, means to feed a preformed wire past said knife member to said die member radially thereof whereby said die member at each rotation of the cutting part cuts off an element from the wire, means to transfer the cut-off element to the forming part, means on said forming part to form the head of the element, means on said setting part to receive the element from the forming part, means to feed a slide fastener tape past said setting part, and means carried by said setting part to bring an element carried thereby into engagement with such tape and to clamp the legs of such element on the tape.

14. A machine for making slide fastener parts comprising a rotating cutter drum, rotating forming drums tangential to each other and one of which is tangential to said cutter drum, and a rotating setting drum tangential to the other of said forming drums, means to drive said drums in synchronism with each other, said cutting drum having a die member on its periphery, a stationary knife member adjacent the periphery of the cutting drum, means to feed a preformed wire past said knife member to said die member whereby said die member at each rotation of the cutting drum cuts off an element from the wire, means to transfer the cut-off element to the first forming drum, means on said forming drums to form the head of the element, means on said setting drum to receive the ele-

ment from the second forming drum, means to feed a slide fastener tape past said setting drum substantially radially thereof, and means carried by said setting drum to bring an element carried thereby into engagement with such tape and to clamp the legs of such element on the tape.

15. In a machine for making slide fastener parts, a rotating setting drum, means to drive said drum continuously at a constant speed, means on said setting drum to receive a slide fastener element, means to feed a slide fastener tape continuously past said setting drum substantially radially thereof, and means carried by said setting drum to bring an element carried thereby into engagement with such tape and to clamp the legs of such element on the tape.

16. In a machine for making slide fastener parts, a rotating forming drum and a rotating setting drum, means to drive said drums continuously at a constant speed, means to feed a slide fastener element to the forming drum, means on said forming drum operable during the transfer of such element to the forming drum to form the head of the element, means on said setting drum to receive the element from the forming drum, means to feed a slide fastener tape past said setting drum, and means carried by said setting drum to bring an element carried thereby into engagement with such tape and to clamp the legs of such element on the tape.

17. In a machine for making slide fastener parts, a rotating member, clamping means carried by said rotating member at a distance from the axis of rotation thereof, said clamping means being adapted to hold a formed slide fastener element in a plane substantially tangential to the circle of rotation with the legs of such element pointing in the direction of rotation, means to feed a fastener tape substantially radially away from said rotating member from a point at a distance from the axis of rotation less than the radius of rotation of said clamping means and in the plane of travel of a fastener carried by such clamping means whereby fastener elements carried by said clamping means engage with their legs over a tape supported by 40 said feeding means, and means to operate such clamping means to clamp the legs of the element on the tape.

18. In a machine for making slide fastener parts, a rotating member, clamping means carried by said rotating member at a distance from the axis of rotation thereof, means to rotate said member continuously at constant speed, said clamping means being adapted to hold a formed slide fastener element in a plane substantially tangential to the circle of rotation with the legs of such element pointing in the direction of rotation, means to feed a fastener tape in the path of travel of a fastener carried by such clamping means, whereby fastener elements carried by said clamping members engage with their legs over a tape supported by said feeding means, means to stop the movement of an element carried by said feeding means upon engagement with the tape, and means to operate such clamping means to clamp the legs of the element on the tape, said last means operating without interfering with the continued rotation of said rotating member.

19. In a machine for making slide fastener parts, a rotating member, clamping means carried by said rotating member at a distance from the axis of rotation thereof, means to rotate said member continuously at constant speed, said clamping means being adapted to hold a formed slide fastener element in a plane substantially tangential to the circle of rotation with the legs of such element pointing in the direction of rotation, means to feed a fastener tape having a bead thereon substantially radially away from said rotating member from a point at a distance from the axis of rotation less than the radius of rotation of said clamping means and in the plane of travel of a fastener carried by such clamping means, whereby fastener elements carried by said clamping means engage with their legs over the bead of a tape supported by said

feeding means, means to stop the movement of an element carried by said feeding means upon engagement with the bead of the tape, and means to operate such clamping means to clamp the legs of the element on the bead of the tape, said last means operating without interfering with the continued rotation of said rotating member.

20. In a machine for making slide fastener parts, a rotating member, clamping means carried by said rotating member at a distance from the axis of rotation thereof, means to rotate said member continuously at constant speed, said clamping means being adapted to hold a formed slide fastener element, means to feed a fastener tape having a head thereon substantially radially away from said rotating member from a point at a distance

15 from the axis of rotation less than the radius of rotation of said clamping means and in the plane of travel of a fastener carried by such clamping means, whereby fastener elements carried by said clamping means engage with their legs over a tape supported by said feeding means, and means to operate such clamping means to clamp the legs of the element on the tape, said last means operating without interfering with the continued rotation of said rotating member.

21. In a machine for making slide fastener parts, a rotating member, clamping means carried by said rotating member at a distance from the axis of rotation thereof, means to rotate said member continuously at constant speed, said clamping means being adapted to hold a formed slide fastener element in a plane substantially tangential to the circle of rotation with the legs of such element pointing in the direction of rotation, means to feed a fastener tape in the plane of travel of a fastener carried by such clamping means, whereby fastener elements carried by said clamping means engage with their legs over a tape supported by said feeding means, means to stop the movement of an element carried by said feeding means upon engagement with the bead of the tape and means to operate such clamping means to clamp the legs of the element on the bead of the tape, said last means operating without interfering with the continued rotation of said rotating member.

22. In a machine as claimed in claim 20, said rotating member comprising a shaft and a drum mounted on said shaft and having a slot therein in a plane transverse to the axis of said shaft, and said tape feeding means guiding the tape through said slot.

23. In a machine as claimed in claim 20, said rotating member comprising a shaft and a drum mounted on said shaft and having a slot therein in a plane transverse to the axis of said shaft, said tape feeding means guiding the tape through said slot, and said clamping means being mounted on said drum above and below said slot.

24. In a machine for making slide fastener parts, a rotating member, clamping means carried by said rotating member at a distance from the axis of rotation thereof, means to rotate said member continuously at constant speed, said clamping means being adapted to hold a formed slide fastener element, means to feed a fastener tape having a head thereon substantially radially away from said rotating member from a point at a distance from the axis of rotation less than the radius of rotation of said clamping means and in the plane of travel of a fastener carried by such clamping means, whereby fastener elements carried by said clamping means engage with their legs over a tape supported by said feeding means, and means to operate such clamping means to clamp the legs of the element on the tape, said last means operating without interfering with the continued rotation of said rotating member, said rotating member comprising a shaft and a drum mounted on said shaft and having a slot therein in a plane transverse to the axis of said shaft, said tape feeding means guiding the tape through said slot, said clamping means comprising levers pivoted on said drum above and below said slot, said levers having adjacent such slot 70 75 opposed diverging faces arranged to receive a fastener ele-

ment therebetween, spring means normally holding said levers in a position in which such faces are divergent, and said operating means being operable when the fastener element engages the tape to swing said levers to bring such faces into parallelism and clamp the legs of the fastener element on the tape.

25. In a machine for making slide fastener parts, a rotating member, clamping means carried by said rotating member at a distance from the axis of rotation thereof, means to rotate said member continuously at constant speed, said clamping means being adapted to hold a formed slide fastener element, means to feed a fastener tape having a head thereon substantially radially away from said rotating member from a point at a distance from the axis of rotation less than the radius of rotation of said clamping means and in the plane of travel of a fastener carried by such clamping means, whereby fastener elements carried by said clamping means engage with their legs over a tape supported by said feeding means, and means to operate such clamping means to clamp the legs of the element on the tape, said last means operating without interfering with the continued rotation of said rotating member, said rotating member comprising a shaft and a drum mounted on said shaft and having a slot therein in a plane transverse to the axis of said shaft, said tape feeding means guiding the tape through said slot, and said clamping means being mounted on said drum above and below said slot and comprising rollers rotatably mounted on said drum above and below said slot, the space between said rollers being not less than the width of the head of a fastener element but less than the width of the legs when extended, so that said rollers hold a fastener element, said rollers when said fastener element is stopped against movement forcing the legs together over the tape guided by said feeding means.

26. In a machine for making slide fastener parts, means for setting fastener elements on a tape comprising a rotatable member comprising a shaft and a drum mounted on said shaft and having a slot therein in a plane transverse to the axis of said shaft, tape feeding means guiding a tape through said slot, and clamping means mounted on said drum above and below said slot.

27. In a machine for making slide fastener parts, means for setting fastener elements on a tape comprising a rotatable member comprising a shaft and a drum mounted on said shaft and having a slot therein in a plane transverse to the axis of said shaft, tape feeding means guiding a tape through said slot, and clamping means mounted on said drum above and below said slot, said clamping means comprising levers pivoted on said drum, said levers having adjacent such slot opposed diverging faces arranged to receive a fastener element therebetween, spring means normally holding said levers in a position in which such faces are divergent, and means operable when the fastener element engages the tape to swing said levers to bring such faces into parallelism and clamp the legs of the fastener element on the tape.

28. In a machine for making slide fastener parts, means for setting fastener elements on a tape comprising a rotatable member comprising a shaft and a drum mounted on said shaft and having a slot therein in a plane transverse to the axis of said shaft, tape feeding means guiding a tape through said slot, and clamping means mounted on said drum above and below said slot, said clamping means comprising rollers rotatably mounted on said drum above and below said slot, the space between said rollers being not less than the width of the head of a fastener element but less than the width of the legs when extended, so that said rollers hold a fastener element, said rollers when said fastener element is stopped against movement forcing the legs together over the tape guided by said feeding means.

29. In a machine for making slide fastener parts, a rotatable drum, levers pivoted on said drum, said levers having opposed diverging faces arranged to receive a fas-

tener element therebetween, spring means normally holding said levers in a position in which such faces are divergent, and means operable when the fastener element engages a tape to swing said levers to bring such faces into parallelism and clamp the legs of the fastener element on the tape.

30. In a machine for making slide fastener parts, a rotatable drum, rollers rotatably mounted on said drum for rotation about axes located in planes transverse to the axis of rotation of the drum, the space between said rollers being not less than the width of the head of a fastener element but less than the width of the legs when extended, so that said rollers hold a fastener element, said rollers when said fastener element is stopped against movement forcing the legs together over a tape.

31. In a machine for making slide fastener parts, a rotary member having means thereon to hold a slide fastener element, said means being open outwardly from the center of said member, means around a part of the periphery of said member to prevent the escape of the element from said holding means under the action of centrifugal force, means including said holding means to cut an element from stock fed thereto, means to feed stock to said last means, and means to eject an element from said holding means.

32. In a machine for making slide fastener parts, drums mounted to rotate in substantially tangential relation to each other, one of said drums having means thereon to hold a slide fastener element, said means being open outwardly from the center of said drum, means around a part of the periphery of said drum to prevent the escape of the element from said holding means under the action of centrifugal force, the other drum having thereon means to receive a fastener element, said escape preventing means terminating at a point short of but closely adjacent the point of tangency of said drums, said holding means comprising a die member, a stationary die knife adjacent the periphery of the first drum, and means to feed a preformed wire past said die knife to said die member radially thereof.

33. In a machine for making slide fastener parts, a rotatable member having means thereon to hold a fastener element, said holding means comprising a die member having an opening therein, a stationary die knife adjacent the periphery of the radius of rotation of said die member, means to feed a preformed wire past said die knife into the opening in said die member, and a movable part carried by said rotatable member behind said opening, said part being movable into said opening to eject an element from said holding means.

34. In a machine for making slide fastener parts, a rotatable member having means thereon to hold a fastener element, said holding means comprising a die member having an opening therein, a stationary die knife adjacent the periphery of the radius of rotation of said die member, means to feed a preformed wire past said die knife into the opening in said die member, and a movable part carried by said rotatable member behind said opening, said part being movable into said opening to eject an element from said holding means, and means intermittently operable to move said part into said opening to interrupt the feed of wire to said die member.

35. In a slide fastener machine, four drums mounted in successive substantially tangential relation with one another to turn about parallel axes, means to drive said drums in synchronism in the same direction, the first drum having on its periphery a die recess, a stationary die knife adjacent the periphery of said first drum, means to feed a preformed strip past said knife to said recess, means around a part of the periphery of the drum to hold a blank cut off by said knife within the recess, said last means terminating at the point of tangency of the first and second drums, said second drum having on its periphery means for receiving such blank, means extending around the second drum from the point of tangency of

the first and second drums to the point of tangency of the second and third drums to hold the blank within the recess of the second drum, a forming member carried on the periphery of the third drum for engaging a blank carried by the blank receiving means of the second drum and forming the head thereof, means to transfer the head-formed blank from the second to the third drum, means extending around the third drum from the point of tangency of the second and third drums to the point of tangency of the third and fourth drums for preventing the escape of the head-formed blank from the third drum, means on the periphery of the fourth drum to grip a head-formed blank from the third drum, means to feed a tape past a point on the periphery of the fourth drum remote from the point of tangency of the third and fourth drums, said gripping means including means operable when they approach such last point to clamp the legs of the head-formed blank on the tape.

36. In a slide fastener machine, four drums mounted in successive substantially tangential relation with one another to turn about parallel axes, means to drive said drums in synchronism in the same direction, said first drum having means associated therewith to cut off a blank from a preformed strip, means around a part of the periphery of the drum to hold a blank cut off by said cutting means from escaping from said drum, said last means terminating at the point of tangency of the first and second drums, said second drum having on its periphery means for receiving such blank, means extending around the second drum from the point of tangency of the first and second drums to the point of tangency of the second and third drums to hold the blank within the recess of the second drum, a forming member carried on the periphery of the third drum for engaging a blank carried by the blank receiving means of the second drum and forming the head thereof, means to transfer the head-formed blank from the second to the third drum, means extending around the third drum from the point of tangency of the second and third drums to the point of tangency of the third and fourth drums for preventing the escape of the head-formed blank from the third drum, means on the periphery of the fourth drum to grip a head-formed blank from the third drum, means to feed a tape past a point on the periphery of the fourth drum remote from the point of tangency of the third and fourth drums, said gripping means including means operable when they approach such last point to clamp the legs of the head-formed blank on the tape.

37. In a slide fastener machine, four drums mounted in successive substantially tangential relation with one another to turn about parallel axes, means to drive said drums in synchronism in the same direction, the first drum having on its periphery a die recess, a stationary die knife adjacent the periphery of said first drum, means to feed a preformed strip past said knife to said recess, means around a part of the periphery of the drum to hold a blank cut off by said knife within the recess, said last means terminating at the point of tangency of the first and second drums, said second drum having on its periphery means for receiving such blank, means extending around the second drum from the point of tangency of the first and second drums to the point of tangency of the second and third drums to hold the blank within the recess of the second drum, a forming member carried on the periphery of the third drum for engaging a blank carried by the blank receiving means of the second drum and forming the head thereof, means to transfer the head-formed blank from the second to the third drum, means extending around the third drum from the point of tangency of the second and third drums to the point of tangency of the third and fourth drums for preventing the escape of the head-formed blank from the third drum, means on the periphery of the fourth drum to grip a head-formed blank from the third drum, and means associated with the fourth drum for setting such head-formed blank on a tape.

38. In a slide fastener machine, four drums mounted in successive substantially tangential relation with one another to turn about parallel axes, means to drive said drums in synchronism in the same direction, said first drum having means associated therewith to cut off a blank from a preformed strip, means around a part of the periphery of the drum to hold a blank cut off by said cutting means from escaping from said drum, said last means terminating at the point of tangency of the first and second drums, said second drum having on its periphery means for receiving such blank, means extending around the second drum from the point of tangency of the first and second drums to the point of tangency of the second and third drums to hold the blank within the recess of the second drum, a forming member carried on the periphery of the third drum for engaging a blank carried by the blank receiving means of the second drum and forming the head thereof, means to transfer the head-formed blank from the second to the third drum, means extending around the third drum from the point of tangency of the second and third drums to the point of tangency of the third and fourth drums for preventing the escape of the head-formed blank from the third drum, means on the periphery of the fourth drum to grip a head-formed blank from the third drum, and means associated with the fourth drum for setting such head-formed blank on a tape.

39. In a fastener making machine, a drum having on its periphery a punch extending radially therefrom and a holding member slightly spaced circumferentially from the punch in the direction of rotation of the drum, means to feed a fastener element blank to a position adjacent the periphery of the drum with its legs pointing in the direction of rotation thereof, and means including said punch for engaging the head of the blank to form a recess therein, said member engaging in the crotch of the legs of the blank.

40. In a machine as claimed in claim 39, said feeding means including a second drum tangential to the first drum and having means on its periphery to hold a blank.

41. In a machine as claimed in claim 40, said holding means being narrower in a direction parallel to the drum axis than the spread of the legs of the blank, and means concentric with said first drum extending to the point of tangency of the drums to engage the portions of the legs of the blank extending beyond said holding means, whereby to transfer the blanks from the second drum to the first drum.

42. A machine for making slide fastener parts from a preformed wire strip comprising a first part mounted to rotate about an axis and having a recess in its periphery of the shape of the cross-section of such strip, a stationary die knife adjacent the periphery of the radius of rotation of the die member, means to feed a preformed wire strip past said die knife to said die member, a second part mounted to rotate about an axis and having means thereon to clamp a slide fastener element on a tape, means to feed a tape past said second part in a path to have elements clamped thereon by said clamping means, and means to transfer an element from said first part to said second part, said transferring means being tangent to said first and second parts and including means to form the head of an element as it is being transferred thereby, means outside the periphery of the first part to prevent escape of a blank from such recess between the cutting point and the point of tangency of said transferring means, and means to rotate said parts and drive said transferring means in synchronism with each other.

43. In a machine as claimed in claim 26, means adjacent the periphery of the member engageable with a fastener element carried thereby to stop the movement of said element, said clamping means acting on the element in response to continued rotation of the member when movement of the element is stopped.

44. In a slide fastener machine, four members mounted

to turn about parallel axes in successive substantially tangential relation with one another, means to drive said members in synchronism in the same direction, said first member having means associated therewith to cut off a blank from a preformed strip and to carry a blank cut off by said cutting means to the point of tangency of the first and second members, said second member having means associated therewith to receive such blank and to carry such blank from the point of tangency of the first and second members to the point of tangency of the second and third members, cooperating means on the second and third members for engaging a blank carried by the second member and forming the head thereof, means to transfer the head-formed blank from the second to the third member, said third member having means associated therewith for carrying such blank from the point of tangency of the second and third members, means associated with the fourth member to grip a head-formed blank from the third member and means associated with the fourth member for setting such head-formed blank on a tape.
